CONDENSATE CONTROL SYSTEM

Lambert A. Hoch, Sioux Falls, S. Dak.

Application May 17, 1941, Serial No. 393,959

3 Claims. (Cl. 237—9)

My invention relates to a condensate control system which is adapted to control the amount of steam to be admitted to a steam heating system or to any processing appliance by means of the amount of condensate, whether by weight or volume. The condensate is caused to accumulate or remain in a special receiver in order to actuate auxiliary devices which govern the admission of steam to the heating system or processing appliances.

A further feature resides in the device used in carrying out my process which is placed in the system that regulates the discharge rate of the condensate and thereby causes to be retained in the special receiver for the actuation of auxiliary steam control devices, all condensate that is in excess of that which can pass through the restrictor at any given instant.

It is a feature to provide a dual compartment receiver in carrying out my method, one of which compartments is the accumulator receiver and the other the restricting chamber.

To more clearly define my method, I have used a series of diagrammatic illustrations which I believe will be helpful in following the steps of my method.

The features set forth, together with other details and objects will be more fully defined throughout the specification and claims.

In the drawing forming a part of this specification:

Figure 1 is a diagrammatic illustration of my condensate control, showing the accumulator receiver and restricting chamber, which operates by volume of the condensate, together with the cooperating parts and auxiliary controls.

Figure 2 is a similar illustration showing the accumulator receiver and restricting chamber in an alternative form, where the control may be governed by the weight of the condensate.

My control A used in carrying out my method consists of an accumulator receiver 2, and a restricting chamber 3, which form a dual compartment receiver with a removable cover 10, the two compartments being connected at the top by the passageway 15 for air or vapor and connected near the bottom by means of a float 9 which operates the valve 5, for the passage of condensate from the compartment 2. The compartment 2 is the accumulator receiver and the inlet for the condensate from the heating system or processing appliance leads into this compartment. The compartment 3 is the restricting chamber and is connected by the air or vapor

opening 15 with the accumulator receiver compartment 2.

The restricting chamber 3 is connected to the condensate return line 11 on the side opposite the inlet controlled by the condensate regulating valve 5. In this condensate discharge outlet 11, is placed an adjustable restrictor valve 6 which may be adjusted to a fixed position. An air loop 4 connects the restricted chamber 3 at the top to the condensate return passage 11 beyond the restrictor. A by-pass 7 with a stop valve 8 connects the accumulator receiver at the bottom to the condensate return line below the restrictor. The restrictor valve 6 and by-pass stop valve 8 may be operated manually or automatically from auxiliary controls, not illustrated in Figures 1 and 2.

I have illustrated diagrammatically in Figure 1 wires 16 and 17 leading from the mercury switch 18 which is located on the cover 10 of the condensate control device A. The mercury switch 18 is adapted to be operated by the float 19 which is located in the condensate accumulator chamber 2, the float 19 being pivoted at 20 and connected to the mercury switch 18 so as to rock the same to operate either the circuit connected with the wires 16 or the wires 17. The float 19 may be maintained in a neutral position as illustrated in Figure 1 by the spring bellows 21 which tends to normally hold the switch 18 in said neutral position.

The switch 18 with its connecting circuits and the float 19 may be operated as an alternative operating means for the condensate control device A. The electric switch 18 is illustrated to show a further alternative form of operation and it will be apparent that the control A may be operated without this alternative switch device as will be hereinafter set forth.

When the switch 18 is used with the control A, the electric circuit not illustrated, controlled by the wires 16 may be adapted to stop the admission of steam or the generation of it when this circuit is closed. When the electric wires connecting the circuit 17 operate to close the circuit which these wires control, said circuit will operate to start the admission of steam or the generation of it. Thus the circuit controlled by the wires 16 may shut off the steam automatically or automatically shut off the combustion device operating to generate steam, and the circuit controlled by the wires 17 may operate to automatically turn on the steam or start the combustion device to cause the generation of steam. Thus it will be apparent that when the

accumulation of condensate in the chamber 2 raises the float to close the circuit control by the wires 16, the steam is shut off or the furnace or combustion mechanism is shut off. When the discharge of the condensate lowers in the chamber 2 and the float 19 operates to close the circuit control by the wires 17, the steam is turned on or the combustion mechanism is started to generate steam.

When my condensate control device A is in operation with the use of the float 19 and the switch 18, the condensation from the heating system or processing device enters the accumulator chamber 2 through the pipe 1. The condensate is then passed to the restricting chamber 3 through the regulating valve 5 and the condensate then passes through the restrictor valve 6 (if the same is open) to the return pipe 11. The return pipe 11 leads to the steam generator, not illustrated, directly or indirectly through a pump or may be wasted or otherwise used. The by-pass valve 8 is normally closed in the ordinary operation of the condensate control device A. When the condensate enters the restricting chamber 3 faster than the restrictor allows it to be discharged, the regulating valve 5 which is operated by the float 9 automatically closes as soon as the condensate rises to a predetermined height in the restricting chamber 3. The amount of condensate in the accumulator chamber 2 may then increase.

The auxiliary float 19 operating the switch 18 controls to increase or decrease the amount of steam admitted from the steam generator as hereinbefore set forth. When the by-pass valve 8 is opened, the operation of the control valves 5 and 6 is nullified.

In the alternative form of my condensate control A, the accumulator receiver compartment 2 is employed with the restricting chamber 3, however, the wall 22 between these chambers is extended to the cover or top 10 so as to separate these compartments from each other. In this form I provide an air by-pass 23 extending from the top of the chamber 2 to the top of the chamber 3. In this alternative form of the controller A, shown in Figure 2, I also provide a regulating device B which is adapted to act as a controller in place of the float 19 and the switch 18 which operates by the weight of the condensate in the chamber 2. In this controller B, I provide a flexible bellows 24 which operates the counter-spring 25. The spring 25 is regulated by the adjustable screw 26 to regulate the tension on the spring. The bellows 24 operates the lever 27 which is pivoted at 28 and in turn operates the mercury switch 29. The switch 29 controls the wires 30 to a similar circuit as the wires 17 are adapted to control, and the wires 31 which operate in a similar manner to the control circuit regulated by the wires 16.

Thus the regulator illustrated in Figure 2 operates in all respects like the controller A in Figure 1, excepting the controller in Figure 2 may operate by the control mechanism B which is caused to operate by the weight of the condensate rather than by the volume.

Therefore it will be apparent that I have illustrated diagrammatically a means adapted to carry out my method of controlling steam input which consists in using the condensate to control the steam output from a steam generator, or to control the steam input into heating apparatus or processing appliances where steam heat is desired and wherein control of the steam is regulated entirely by the steam condensate.

In the operation of my controllers A, when condensate returns from the heating system and/or processing appliance, it collects in the accumulator receiver 2 and allows the air and vapor to pass on through the air or vapor outlet 15 to the restricting chamber 3 and on through the air loop 4 to the return line 11 beyond the restrictor 3. When the condensate reaches a certain level, it will flow through the water level restricting mechanism 5 to the restricting chamber 3. When the level in the restricting chamber 3 rises to a given point, the valve will shut and prevent the flow from the accumulator 2 to the restricting chamber 3. Additional condensate entering the accumulator at this time will raise the level in the accumulator and actuate a float 19 or other auxiliary control device which will in turn operate the steam valve or combustion device controlling the admission of steam to the heating system and/or processing appliance. The water admitted to the restricting chamber may be controllably discharged by the fixed or variable restrictor valve 6. The rate of flow through the restrictor is kept uniform (for practical purposes) by means of the balance line or air loop which equalizes the pressure on each side of the restrictor and by reason of the water level restricting mechanism that prevents the water from rising in the restricting chamber and increasing the head on the initial side of the restrictor. The greater the area of the discharge port in the restrictor, the faster will be the flow of condensate from the restricting chamber, and the faster will be the flow from the accumulator 25 to the restricting chamber which will cause the water level in the accumulator to remain lower and thus to actuate the auxiliary steam control mechanism by means of a float, or some other mechanism to admit more steam. The admission of more steam causes more condensate and when the condensate returns to the accumulator receiver faster than it is discharged, the level will rise and actuate the steam control mechanism to reduce the amount of steam being admitted. Thus the amount of steam that is admitted to the heating system and/or processing appliance will be determined by the discharge area of the restrictor. The setting of the restrictor may be made manually or automatically by auxiliary control devices above set forth.

The auxiliary steam control devices that are actuated by the amount of water accumulating in the accumulator receiver, whether by weight or volume, may be of the "on-off" type so that a predetermined increase of condensate in the accumulator causes the steam admitting devices to be shut off and to be turned on again when the condensate has been lessened to a predetermined amount; or the amount of steam admitted may be increased or decreased gradually according to the amount of the condensate in the accumulator decreasing or increasing.

The by-pass stop valve may be operated manually or automatically by other auxiliary controls. Its function is to allow free drainage of the condensate and thus to allow a continuous flow of steam to the heating system and/or processing device without interference from the restrictor.

A flexible diaphragm and/or flexible bellows may be connected to the bottom of the accumulator receiver and with an adjustable or fixed counter spring so that the weight of the condensate in the accumulator may actuate aux-

illary steam control devices through the dia-phragm or flexible bellows thus installed.

My basic idea is that as the amount of steam admitted to a heating system or processing appliance for practical purposes may be measured by the amount of condensate derived therefrom, so likewise the amount of steam admitted to a heating system or processing appliance for practical purposes may be controlled by the amount of condensate derived therefrom.

Secondly, only a given amount of condensate at a given temperature will pass through an orifice (of a given size) at a given differential of pressures on each side of the orifice. Accordingly, if I control the differential and the orifice size, I control for practical purposes the amount of condensate that will pass through this orifice. Hence, by determining the orifice size and the differential across the orifice, I can cause all condensate returning from the heating system and/or processing device to accumulate when it is in excess of the amount that can pass through the orifice at the given differential. This excess condensate can then actuate an auxiliary control to retard the admission of steam and thereby lessen the consequent amount of condensate return, until the excess has been able to pass through this orifice when the lessened amount of excess will in turn actuate an auxiliary control to increase the supply of steam so as to increase the amount of condensate returning. As a consequence, by controlling the discharge of condensate, I control the amount of steam admitted to the heating system and/or processing device.

In accordance with the patent statutes, I have described the principles of my method of controlling the input of steam by the condensate therefrom; and while I have illustrated certain apparatus in a diagrammatic manner, I desire to have it understood that the same is only illustrative of a means of carrying out my method, and that other apparatus and means may be employed without departing from the spirit of my invention within the scope of the following claims.

I claim:

1. A control for controlling the input of live steam to heating units and appliances from a steam generator, said control comprising an accumulator receiver and a restricting chamber, a float controlled valve means in said restricting chamber, said float controlled valve means adapted to regulate the flow of condensate from said accumulator receiver into said restricting chamber, an air passage connecting said accumulator to said restricting chamber, a condensate return line leading from said restricting chamber to the steam generator, valve means regulating the flow of condensate from said restricting chamber into said condensate return, an air passage connecting said restricting chamber

to said condensate return, a switch, a float positioned within said accumulator receiver and connected to said switch, said float adapted to actuate said switch upon an increase or decrease of volume of condensate in said accumulator receiver, and said switch adapted to control the valve means which regulates the output of live steam from said steam generator.

2. A control for controlling steam input of live steam to heating units and appliances from a steam generator, said control comprising an accumulator receiver and a restricting chamber, a float controlled valve means in said restricting chamber, said float controlled valve connecting said accumulator receiver to said restricting chamber, a switch, a float positioned within said accumulator receiver and connected to said switch, said float adapted to actuate said switch upon an increase or decrease of condensate in said accumulator receiver, said float control valve adapted to regulate the flow of condensate from said accumulator receiver into said restricting chamber, a passageway leading from said restricting chamber to the steam generator, valve means for regulating the flow of condensate to said steam generator from said restricting chamber, a by-pass leading from said accumulator to said condensate return line, said by-pass by-passing said valve means, a restrictor valve positioned in said by-pass adapted to control the flow of liquid in said by-pass, and said switch adapted to control the valve means which regulates the input of steam to said heating units and appliances from said steam generator.

3. In a steam heating system, a control device for controlling steam input from a steam generator, said control device comprising an accumulator chamber and a restricting chamber, a float controlled valve means in said restricting chamber, said float controlled valve means connecting the bottoms of said chambers, said float controlled valve adapted to open up a decrease of condensate in said restricting chamber and to close upon an increase of condensate in said restricting chamber, a condensate return line leading from said restricting chamber to the steam generator, adjustable valve means regulating the flow of condensate from said restricting chamber into said condensate return, an air passageway connecting said restricting chamber to said condensate return, an air passageway connecting the top ends of said chambers, a mercury switch, a float positioned within said accumulating chamber and connected to said switch, said float adapted to actuate said switch upon an increase or decrease of the condensate of the used steam, and said switch adapted to control the valve means which regulates the input of live steam from the heat generator into said heating system.

LAMBERT A. HOCH.
